ALONZO A. ANDERSON, OF WOODSTOCK, ILLINOIS, ASSIGNOR TO THE
OLIVER TYPEWRITER COMPANY, OF CHICAGO, ILLINOIS, A CORPO-
RATION OF ILLINOIS.

MARGINAL PAPER-GUIDE FOR TYPE-WRITING MACHINES.

No. 829,063.

Specification of Letters Patent.

Patented Aug. 21, 1906.

Application filed May 9, 1904. Serial No. 207,094.

To all whom it may concern:

Be it known that I, ALONZO A. ANDERSON, a citizen of the United States, and a resident of Woodstock, in the county of McHenry and State of Illinois, have invented certain new and useful Improvements in Marginal Paper-Guides for Type-Writing Machines; and I do hereby declare that the following is a full, clear, and exact description thereof, reference being had to the accompanying drawings, and to the letters of reference marked thereon, which form a part of this specification.

This invention relates to improvements in a novel paper-guide for the carriages of type-writing machines; and the invention consists in the matters hereinafter set forth, and more particularly pointed out in the appended claims.

My novel paper-guide is adapted for attachment to the left-hand end of the paper-shield or guide-plate located at the entering side of the carriage of a type-writing machine in position to engage and direct the left-hand margin of a sheet of paper as it is being inserted into the carriage, whereby the advance margin of the sheet is squared relatively to the axis of the carriage-platen, and the side edges of the sheet are located in desired relation to the ends of the platen or the printing-point. Said paper-guide is herein shown as applied to the paper-carriage of an "Oliver" type-writing machine, and in this adaptation it is attached to the lower paper-shield or guide-plate at the rear or entering side of the carriage. Said marginal guide is connected with the paper-shield in such manner as to enable the guide to be shifted or adjusted lengthwise of the carriage, while being held or retained with sufficient firmness to hold the same from accidental displacement.

In the drawings, Figure 1 is a plan view of the carriage of an Oliver type-writing machine, showing my marginal guide attached thereto. Fig. 2 is a cross-section of the carriage. Fig. 3 is a perspective view of the marginal guide removed from the other parts of the machine. Fig. 4 is a detail section taken through the paper-shield and guide at right angles to the guide to show the manner of fastening the guide in place.

As shown in the drawings, A A designate the end members of the carriage, connected

by longitudinal members A' A'', upon the former of which is formed the rack-bar of the letter-spacing mechanism.

B designates the usual platen, and B' B'' B''' the presser-rollers for pressing the paper against the platen.

B⁴ B⁵ designate curved paper-guides for directing an entering sheet of paper from one roll to the other, and B⁶ B⁶ adjustable guides for guiding the paper around the upper side of the platen.

C C' designate the upper and lower paper guides or shields located in rear of the platen or at the entering side of the carriage, said shields extending between and being attached to the end plates of the carriage.

My improved left-hand margin paper-guide is applied to the upper face of the lower paper-shield or guide-plate C'. Said marginal guide consists of a narrow plate or bar D, which is located at the left-hand end and on the upper face of the paper-shield C' and at right angles to the axis of the platen. The upper paper-shield or guide-plate C is broken away at the left-hand side of the carriage to better exhibit the marginal guide. Said bar is made of some thickness, so as to insure the left-hand margin of the paper striking the same when being inserted into the carriage. It is made of a length to bring its inner end near the platen. Said marginal guide-bar D is attached to the paper-shield C' by means of rivets d and permitting it to be adjusted longitudinally of the carriage to accommodate the carriage to sheets of varying widths. The means for attaching the bar D to the paper-shield C' and permitting of such longitudinal adjustment is made as follows: Attached to the guide-bar D by means of rivets d and disposed at right angles thereto is a block D', made somewhat thicker than the guide-bar, and said block D' is fitted to and slides with a groove c, extending longitudinally of the paper-shield or guide-plate C', said groove being located midway between the side margins of the shield. The attaching-block D' is made of such thickness that while it is flush at its upper surface with the upper face of the paper-shield C' it extends at its lower side some distance below the lower face of said paper-shield, as clearly shown in Fig. 4.

The parts are held yieldingly in place on the paper shield or guide C' by means of a

spring-plate D^2 , which is attached to the lower face of the attaching-block D' , as by means of a screw d' , and is provided at its other end with separated arms d^2 d^2 , which are bent or deflected upwardly and engage the lower face of the paper-shield one on each side of said slot c and block D' . Said spring-plate D^2 is affixed to the attaching-block after the said block has been inserted in said groove. The resiliency of the spring-arms d^2 is such as to bear upwardly against the paper-shield with sufficient force to hold the parts from accidental displacement in the ordinary use of the device, while permitting the guide-bar to be moved freely longitudinally of the carriage when it is desired to adjust the device for paper of different width.

It is obvious that if the sheet of paper be pressed with its left-hand margin against the marginal guide-bar D the paper will be squared so as to enter the carriage with its advance margin parallel with the axis of the platen. By reason of the fact that said guide-bar extends a distance above the face of the lower paper-shield it is in position to be readily engaged by the margin of the paper when the paper is being inserted into the machine and requires no manipulation of the guide for this purpose. The marginal guide-bar may be moved inwardly to the limit of the slot or at any intermediate point, as indicated in Fig. 1, so as to locate the side edges of the sheet in a desired position with respect to the ends of the platen or the printing-point. The guide may therefore be adapted to narrow sheets of paper or to postal cards, so that it preserves for such narrow sheets or postal cards the same accurate guiding of the sheets when being inserted into the machine as it provides for the wider sheets.

The device herein shown is susceptible to variations in its structural details to adapt it

to different machines, and I do not wish to be limited to the exact construction shown except as hereinafter made the subject of specific claims.

I claim as my invention—

1. The combination with the carriage and platen of a type-writing machine, of a paper-shield on the entering side of said platen provided with a longitudinal slot, a marginal guide-bar resting on the top surface of the paper-shield and extending at right angles thereto, a guide-block attached to the said guide-bar at right angles thereto, said block being of the same width as the slot and extending inwardly from the guide-bar, and spring-arms attached to said guide-block and pressing on the under surface of the shield beneath or opposite the guide-bar.

2. The combination with the carriage and platen of a type-writing machine, of a paper-shield on the entering side of said platen provided with a longitudinal slot, a marginal guide-bar resting on the top surface of the paper-shield and extending at right angles thereto, a guide-block attached to the said guide-bar at right angles thereto, said block being of the same width as the slot and extending inwardly from the guide-bar, and a spring-plate attached to the under surface of the guide-block at its inner end and provided with two laterally-separated arms, one located at each side of said guide-block, the free ends of said arms being adapted to bear on the under side of the paper-shield beneath or opposite the guide-bar.

In testimony that I claim the foregoing as my invention I affix my signature, in presence of two witnesses, this 3d day of May, A. D. 1904.

ALONZO A. ANDERSON.
